UNITED STATES PATENT OFFICE.

HENRY A. RUST, OF HOPEWELL, VIRGINIA.

HAT ATTACHMENT.

1,324,412.

Specification of Letters Patent.

Patented Dec. 9, 1919.

Application filed January 8, 1919. Serial No. 270,122.

To all whom it may concern:

Be it known that I, HENRY A. RUST, a citizen of the United States of America, and a resident of Hopewell, county of 5 Prince George, and State of Virginia, have invented certain new and useful Improvements in Hat Attachments, of which the following is a full and clear specification.

The object of this invention is to provide 10 a simple attachment for insertion in a soft felt hat to support the crown in its folded position, as more fully hereinafter set forth.

In the drawing—

Figure 1 is a perspective view of the device detached; and

Fig. 2 is a transverse sectional view of a hat with the device applied thereto.

The invention consists essentially of a pair of flexible members preferably steel 20 wires *a*, although any other flexible material, such as reed, rattan or celluloid, may be employed; and it is obvious also that the wire or other members may be suitably covered with a fabric of a pleasing color 25 so as not to be conspicuous in the hat and so also that they may, in fact, add to the ornamental appearance of the hat. These members are attached together at their ends in any suitable manner. In the drawing, I 30 have shown them attached by a thin flat piece of sheet metal *b*, whose edges are crimped over the ends of the wires to thus rigidly secure them together. The wire members are separated a suitable distance 35 so as to receive between them the longitudinal central crease in the hat-crown, as now is vogue. The wires are sufficiently separated to receive this central longitudinal crease in the crown, and they are sufficiently 40 light and flexible to avoid giving any stiff and unnatural appearance to the crown. They are elastic, *i. e.*, of springy wire, rattan, celluloid or reed, so as to naturally shape themselves to the crown, though in all 45 cases, it will be understood, they must not be sufficiently stiff or rigid to give an unnatural shape to the crown or prevent crushing-in of the crown upon the application of unusual force. In other words, these 50 supporting members will be sufficiently flexible in any event to permit the crown of the hat to be temporarily indented or

crushed without injury to the wires, and it will be understood also that these devices may be made separately from the hat and 55 sold as attachments. It will also be understood that the elasticity of the wires permits them to be bowed or flexed into shape by the retailer when sold to the wearer and fitted into his hat, these light, thin wires 60 insuring a nice fitting to the particular conformation of the crown and without in the least distorting the crown.

It will be understood also that when the device is applied to the hat, the ends of the 65 distending members and the means for fastening them together will lie between the sweat-band and the body of the crown, so as not only to be concealed from view, but also so that they will not render the device 70 uncomfortable to the wearer, it being understood that in all cases the distending members and their fastening devices will be made sufficiently thin and light to avoid any undue bulging of the hat-band, or exert any uncomfortable pressure on the head of the wearer. In practice, I have found that it is easily possible to make the ends of the bows and their fastening devices sufficiently thin and light in weight to permit 75 80 them to be so completely protected by the thickness of the sweat-band as to be entirely unnoticeable to the wearer.

The nature and scope of the invention having been thus indicated and its preferred 85 embodiment having been specifically described what is claimed as new is:

In a hat shape-retainer of the class set forth, a pair of thin light elastic laterally-yieldable members, said members being 90 spaced apart, a pair of thin plates secured to the ends of said elastic members and forming anchoring means for said elastic members and holding them in their spaced relation and adapted to be inserted between the 95 sweat-band and the crown, said elastic members being adapted to be flexed into a curved position when inserted in a hat and to fit their entire length against the crown of the hat. 100

In testimony whereof I hereunto affix my signature.

H. A. RUST.
